MACHINE FOR OPERATING ON STITCH-DOWN SHOES

Fred Ricks and Cyril Harry James, Leicester, England, assignors to United Shoe Machinery Corporation, Paterson, N. J., a corporation of New Jersey

Application November 4, 1936, Serial No. 109,133
In Great Britain November 21, 1935

19. Claims. (Cl. 12—7)

This invention relates to machines for operating upon the end portions of shoes and is illustrated as embodied in a machine for working the foreparts of stitchdown shoe uppers into last-ed position and for pressing the outturned flanges thereof against the projecting margins of soles.

Such machines are adapted for shaping the toe portions of the uppers of stitchdown shoes to their lasts, forming outwardly turned marginal flanges thereon and at the same operation securing the flanges to the sole margin by the aid of adhesive, said machines being equipped each with a pair of wipers which are arranged to embrace the toe portion of the shoe at a level above the shoe bottom and with a sole support, the wipers and the sole support being arranged for relative movement heightwise of the shoe to effect a wiping action toward the sole to shape the toe portion of the upper to the last and to press the outturned marginal portion of the upper against the marginal portion of the sole which extends outwardly beyond the sides of the last. At the conclusion of the relative heightwise movement of the wipers and shoe support the wipers are given a slight advancing and closing movement to form a well defined crease on the upper between the marginal portion of the upper overlying the outwardly extending portion of the sole and the portion of the upper which is conformed to the side of the last.

Objects of this invention are to provide improved mechanism for tensioning the upper at the end and sides of the toe to obtain adequate and complete tensioning thereof over the last prior to the action of the wipers and to effect tensioning of the upper in directions and to an extent which will be satisfactory under all conditions.

With these objects in view, the invention comprises, as herein illustrated, the combination of end-embracing wipers movable heightwise of the shoe and toe and side grippers mounted upon a sole support and arranged to move away from a last on the support in divergent paths so that the upper extending between the grippers will be held in a tensioned condition to facilitate the laying of those portions free from wrinkles upon the outwardly extending marginal portion of the sole by later action of the wipers. Preferably and as illustrated, each gripper is movable about a pivot located under the sole support, and the gripper jaws are initially located above and over the sole support, their movement being outwardly with respect to the last with a component of heightwise movement to cause the jaws at the

conclusion of the pulling movement to be located below the upper surface of the sole support so that they will not interfere with the action of the wipers. As illustrated, the pivots of the side grippers are in non-parallel relation to each other and converge toward a point in front of the shoe so that their action in imparting to the upper a tension directed toward of the shoe has a marked tendency to draw the opposite sides of the upper extending along the shank of the shoe closely against the last, thus assisting in the production of a well shaped shoe. In the illustrated construction, the grippers are closed and moved in the described manner to tension the upper independently of the wipers by depression of a treadle and means is provided for holding them in upper-tensioning position until after the operation of the wipers, which means is automatically released by the return of the wipers to their normal position.

The illustrated machine is equipped with mechanism desirable under some conditions to cause the toe gripper to close and apply light tension to the upper prior to the action of the side grippers and to cause the toe gripper further to pull the upper and then to release it during the action of the wipers. This mechanism is preferably arranged, as illustrated, so that it can be used or not at the will of the operator.

When, in the operation of the illustrated machine, the grippers are operated to pull the margin of the shoe upper heightwise over the last and outwardly away from the sides of the last so far that when they have finished their upper-pulling movements they hold the extreme edge of the margin close against the edge of the projecting margin of the sole substantially on the same level as that face of the sole against which the margin of the upper is to be pressed by the wipers, the margin of the upper is in such condition that when the wipers are operated heightwise of the shoe they can readily press the tensioned margin of the upper uniformly flat against the margin of the sole projecting outwardly beyond the sides of the last. Under these conditions the grippers may be depended upon to tension the upper instead of depending largely upon the wiping action of the wipers as in prior constructions, with the advantage that, when working on certain kinds of shoes, for instance shoes having uppers made of relatively soft material such as glacé leather or tinsel fabric, damage to the upper by the wiping action of the wipers is avoided.

These and other features of the invention will

appear more fully from the following description when read in connection with the accompanying drawings and will be pointed out in the appended claims.

5 In the drawings,

Fig. 1 is a side view of the upper portion of a machine embodying the present invention;

Fig. 2 is a sectional view of the wipers and work support taken in front of the side grippers;

10 Fig. 3 is a plan view illustrating the wipers and the gripper mechanism with which the machine is provided;

Fig. 4 is a view illustrating power-operated means for actuating the wipers and the rear abutment; and

15 Fig. 5 is a detail of one of the side grippers in its initial position.

As in prior machines for this work, the machine is preferably duplex, two separate machines being arranged side by side, one adapted for operating on the left shoe of a pair and the other for operating on the right. Since, except for the fact that wipers of the respective machines will differ in shape to fit right and left shoes respectively, the machines may be identical, the following description may be assumed to apply to each one. Each machine comprises an upright column or post 10 which is inclined toward the operator at some 30 degrees to the vertical. On its upper end the post carries a readily detachable sole-supporting plate 12 adapted to receive the fore-part of the sole of a stitchdown shoe presented right side up to the machine. The plate 12 is of a shape roughly similar to that of the fore-part of a sole and is arranged perpendicular to the direction of the post 10 so that it slopes upwardly away from the operator so that a shoe presented thereon will be in a convenient position for the operator to look down upon it and watch the progress of the operation on the shoe. The plate 12 is secured to the post 10 by a screw 14 (Fig. 3) passing through a slot in the plate 12 to permit adjustment of the plate lengthwise of the shoe and relatively to wipers 16 with which the machine is equipped. The inner marginal portions of the wipers overlie the marginal portion of the plate 12 around the toe portion of the shoe, the wipers normally occupying a raised position, as indicated in Fig. 2, spaced well above the plate 12. The toe end of the plate 12 has an upstanding rib 18 (Fig. 1) against which the toe end of a sole A on the bottom of a last B within the upper C of a shoe may be caused to abut and position the shoe longitudinally in the machine relatively to the wipers.

55 At the rear of the machine there is provided a slideway 20 upon which is mounted a rising and falling wiper-carrying bracket 22, this slideway extending substantially perpendicular to the plane in which the sole-supporting plate 12 lies. The bracket 22 has an upper portion 24 parallel to the plate 12 which forms a guideway for a wiper-carrying slide 26. The slide 26 at its forward end has formed in it arcuate guideways 28 (Fig. 2) for a pair of wiper-carrying plates 30 lying parallel to and above the sole-supporting plate 12, the inner edges of the wipers 16 carried thereby being shaped similar to the toe portion of the shoe to be operated on and the inner edges of the wipers 16 being long enough to extend somewhat beyond those points at the opposite sides of the shoe where the ends of the tip seam are usually located. The two wipers abut against each other at that point which lies opposite the toe end of the shoe, and the arcuate

guideways 28 for the wiper-carrying plates 30 are concentric about the meeting point of the wiper 16. The outer edges of the wiper-carrying plates 30 are also concentric about said meeting point and have rack teeth 32 formed on their outer edges. A pinion 34 is provided to mesh with the rack teeth on each wiper-carrying plate 28, and the two pinions are freely rotatable about pins 36 secured to the wiper-carrying slide 26. Fast on the upper face of each of the pinions 34 is a second pinion 38 which engages a rack bar 40 arranged for adjustment longitudinally parallel to the direction of movement of the wiper-carrying slide 26. The two rack bars 40, 40 are parallel and lie in directions lengthwise of the shoe in the machine and their rear ends are connected by a bridge piece 42 extending transversely across and over the slide 26 and arranged to slide forwardly and rearwardly on ways 43 formed on a lug 44 projecting upwardly from the midportion of the bracket 22 through a slot 46 in the slide 26. Through the lug 44 a rod 48 is threaded, the rod extending parallel to the rack bars 40 and having collars 50, 50 abutting against the opposite sides of an ear 52 extending upwardly from the bridge piece 42. By rotating a hand wheel 54 on the rod 48 the rack bars 40 may be moved lengthwise of the shoe relatively to the wiper-carrying slide 26 to rotate the pinions 34, 38 and thus cause the wipers to move angularly about their meeting point so that the forward portions of their wiping edges may be spaced apart a distance corresponding to the width of the portion of the shoe they are to operate upon.

35 It is desirable that the wipers, while embracing the toe portion of the shoe with the desired closeness, be moved heightwise of the shoe from a level above that of the upper face of the sole downwardly toward the sole to press the margin of the upper held under tension and outspread by grippers, in a manner to be hereinafter described, against the sole and should, when they actually press the margin of the upper against the sole, be caused to advance slightly toward the heel end of the shoe and to swing toward each other as they do so in order to force the upper inwardly close against the last and to form a well defined crease on the upper between the outwardly extending margin of the upper and the portion of the upper extending over the last.

50 To cause the wipers to move in this manner, a bell crank lever 60 is pivoted on a transverse horizontal pivot 62 to the rising and falling bracket 22, and a forwardly extending arm of the lever 60 has secured to it the upper end of a link 64 which at its lower end is connected to means, later to be described, for operating it by power. An upwardly extending arm of the bell crank 60 is provided with a segment 66 having teeth 68 formed thereon which mesh with teeth formed on the lower side of the wiper-carrying slide 26, so that downward movement of the link 64 will rotate the segment 66 and cause the wiper-carrying slide 26 to be moved toward the shoe. A relatively strong spring 70 is located between the rear end of the slot 46 in the wiper-carrying slide 26 and the lug 44 on the bracket 22 and tends not only to maintain the wiper-carrying slide 26 in a definite rearward position but thus holds the wipers in a definite separated and retracted position as determined by adjustment of the hand wheel 54 such that the wipers may bear evenly against the different parts of the portion of the upper extending around the 75

toe portion of the last as they move downwardly toward the sole. Since the spring 70 resists advancing movement of the wiper-carrying slide and therefore swinging movement of the bell crank lever 60, the effect of downward movement of the link 64 will be to cause the bracket 22 to descend until the wipers, in moving downwardly around the toe portion of the shoe uppers, press the outwardly extending margin of the upper which at that time will be held under tension by grippers in the manner hereinafter described, firmly against the outwardly extending margin of the sole. When the resistance offered by the sole supported on the plate 12 to further downward movement of the wipers exceeds the resistance offered by the spring 70 to advancing movement of the wiper slide 26, the spring yields and the wiper slide advances a short distance toward the heel end of the shoe, thus causing the wipers 16 to advance and also to close as they do so owing to the fact that the pinions 36, 36 carried by the wiper slide 26 move relatively to the racks 40 which are held from forward movement. As the wipers thus advance and close, their inner edges are forced into the angle between the side of the last and the margin of the sole which extends outwardly beyond the last and thus crowd the upper inwardly against the last and produce a well defined crease on the upper between its outwardly extending margin and the portion thereof which extends over the last.

For operating the link 64 its lower end (Fig. 4) may be connected to a cross-head 72 mounted on the lower end of a piston rod 74 which passes through a stuffing box 76 in the head of a cylinder 78 and is connected to a piston in the cylinder. Preferably there is another link 64 on the opposite side of the cylinder connected to the same head 72 and to the bell crank lever 60. Compressed air supplied by a pipe 80 is conducted by a pipe 82 to the lower end of the cylinder 78 and by a pipe 84 to its upper end, the supply of air to the cylinder being controlled by a valve 86 operated through a link 88 by a treadle lever 90 pivoted at 92 to the frame and having a treadle 94 pivoted thereto at 95 and located at the front of the machine. A lug 97 on the treadle 94 engages a part of the treadle lever 90 to prevent clockwise movement of the treadle 94. In the position shown the valve 86 is turned to supply air to the lower end of the cylinder through the pipe 82 and when the treadle 94 is depressed against a spring 96 the valve is turned in a position to supply air through the pipe 84 to the upper end of the cylinder, causing the piston and the links 64 to move downwardly and operate the wipers in the manner described. When the treadle 94 is fully depressed a latch 98 pivoted at 99 to the lever 90 engages under a ledge 100 on the frame and holds the treadle in depressed position and the wipers in pressing relation to the upper. The shoe is preferably left in the machine until another shoe has been similarly treated in a similar manner in another machine and is then released by depressing an arm 102 formed on the treadle 94 and held in raised position by a spring 104 connected between a downward projection on the latch 98 and a similar downward projection on the treadle 94. The arm 102 engages a lug 106 on the latch 98 and swings it forwardly out from under the ledge 100, thus releasing the treadle, the spring 96 then acting to restore the valve to the position

shown, thereby exhausting the air from the upper end of the cylinder and introducing air to the lower end, whereupon the links 64 are moved upwardly to restore the wiper mechanism to its initial position.

In order to prevent the shoe from being pushed rearwardly during the advancing and closing movement of the wipers, an abutment 108 is arranged to be brought into engagement with the rear end of the shoe by the described movement of the links 64. The abutment 108 is mounted on a member 110 which is longitudinally adjustable with respect to a lever 112 pivoted at 114 to the machine frame. The rear end of the lever 112 carries a roll 116 which normally engages a low portion of a cam 118 pivoted at 120 on the machine frame. Pivoted at 122 to the cam 120 is a link 124 having at its lower end a slot 126 through which passes a pin 128 on an arm 130 rigidly secured to one of the links 64.

Between the pin 128 on the arm 130 and a pin 132 on the cam 118 is a tension spring 134 and during the downward movement of the link 64 the spring 134 will be tensioned and the cam 118 rotated in a counterclockwise direction, forcing the high part 136 of the cam against the roll 116 to tip the lever 112 in a counterclockwise direction to bring the abutment 108 into engagement with the rear end of the shoe and hold it positively against the lug 106 on the plate 12 while the advancing and closing movements of the wipers take place.

The novel gripper mechanism with which the illustrated machine is equipped, as shown in Figs. 1, 2, 3 and 5, comprises a toe gripper located at 35 the toe end of the supporting plate 12 so that it will engage the margin of that portion of the upper which extends across the toe end of the last and two side grippers located on the opposite sides of the sole-supporting plate 12 approximately in the regions of the ends of the tip seam. The jaws of the toe gripper are relatively wide (for example 1 3/4 inches in width) in order that they may grip a substantial portion of upper extending across the toe end of the last. The side grippers may be narrower (for example about an inch in width). Conveniently the inner edges of the jaws of the toe gripper may, as seen in plan (Fig. 3), be curved to approximate the curvature of the toe end of the last so that the opposite side portions of the gripper may engage the margin of the upper as close to the last as does the central portion of the gripper.

The toe gripper (Fig. 1) comprises a lower jaw member 140 pivoted at 142 to a member 144 fixed to the top of the post 10 and supporting the sole-supporting plate 12. The lower jaw 146 of the gripper is formed as an upward projection of the jaw member 140 and is arranged to overhang somewhat the toe end of the plate 12. An upper jaw 148 is pivoted at 150 to the jaw member 140, and a rearward extension thereof is connected by a link 152 to a short lever 154 pivoted between its ends at 156 to the member 140. The front end of the lever 154 is pivoted at 158 to a rod 160 which passes downwardly through an ear 162 pivoted to a slide 164 mounted for movement in the frame in a direction perpendicular to the plate 12. On the rod 160 between the ear 162 and set nuts 166 on the end of the rod is a compression spring 168. On the slide 164 is a pin 165 which carries the upper end of a rod 167 which at its lower end is connected to a treadle 169, and a tension spring 171 is connected between the slide 164 and the post 10 to return the

slide to its upper position. It will be seen that downward movement of the slide 164 will act through the spring 168 to rock the lever 154, push upward on the link 152 and cause the upper jaw 148 of the toe gripper to move toward the lower jaw and grip the upper. To a downwardly extending ear on the jaw member 140 is pivoted at 170 the bifurcated head of a rod 172 which extends forwardly through an ear 174 10 projecting downwardly from the plate 144. Between the head of the rod 172 and the ear 174 is a compression spring 176 which is lighter than the spring 168 on the rod 160. The spring 176 maintains the jaw 146 in its initial position which 15 is determined by adjustment of a nut 178 on the rod 172 and insures that the jaw 148 will first move to grip the upper against the jaw 146 and then permit the toe gripper as a whole to turn about the pivot 142 to swing the gripper jaws 20 downwardly and rearwardly in response to the downward movement of the slide 164.

The side grippers are alike and each comprises a lower jaw member 180 and an upper jaw member 182 (Fig. 5). Each lower jaw member has 25 an upward extension forming the lower jaw 184 of the gripper, said extension being inwardly inclined to overlie slightly the plate 12 and to present the jaw 184 parallel to and substantially in the plane of the upper surface of the sole A 30 located on the supporting plate 12. The jaw member 180 is pivoted at 186 to the member 144 at a point substantially under the edge of the bottom of the last B located with its sole A on the plate 12. The upper jaw 182 is pivoted at 188 35 to the jaw member 180, and connected to it between its pivot and its jaw portion 189 is a depending rod 190 the lower end of which is pivoted at 192 (Fig. 1) to the slide 164 so that downward movement of the slide will close the upper jaw 40 189 against the lower jaw 184 to seize the upper C. The jaw member 180 is supported in its initial position by a spring 194 threaded on a rod 196 which, at its upper end, is pivoted at 198 45 to the jaw member 180 and at its lower end passes freely through an arm 200 on the post 10. Set nuts 202 on the lower end of the rod 196 limit 50 upward movement of the jaw member 180 and adjustably determine its initial position. The spring 194 insures that the jaws will close upon 55 the upper C before they swing about the pivot 186 to impart an outward and downward pull to the upper.

It will be seen that the three grippers are so constructed and arranged that by downward movement of the slide 164 the upper jaws will be moved relatively to the lower jaws to grip the shoe upper and that thereafter the gripping jaws will hold the upper taut against the upper face of the last by tensions exerted on it in outward 60 and downward directions. The toe gripper, by its downward movement with a component away from the shoe, imparts a lengthwise tension to the shoe upper in addition to a heightwise tension and the side grippers are so arranged that as they 65 move outwardly they have an appreciable component of movement lengthwise of the shoe toward the toe end, and for this purpose the pivots 186 of the side grippers, as shown in Fig. 3, are inclined at an angle of about 15 degrees to the 70 longitudinal median line of the sole A so that the axes of the pivots when extended converge and meet at a point located beyond the toe end of the sole. Thus, as the toe and opposite side grippers swing outwardly and downwardly in the manner 75 above described, the portion of the upper lying

across the toe portion of the last is subjected to a tension which extends both lengthwise of the shoe and downwardly while those opposite side portions of the upper which are gripped by the side gripper are subjected to a downward tension 5 which has an appreciable component lengthwise of the last as well as widthwise of the last. Thus the grippers, in addition to shaping the toe portion of the upper tightly to the upper face of the last, draw the opposite sides of the shank portion 10 of the shoe upper closely against the sides of the last and stretch the toe portion of the shoe upper and hold it in such an outspread condition that the portions of the upper extending between adjacent grippers will be subjected to sufficient 15 stretching action to eliminate from them any substantial wrinkles therein. Furthermore, when the grippers have completed their movements the portion of the upper which they are gripping will be held in stretched condition with its outer edge 20 slightly below the level of the upper face of the sole A on the supporting plate 12 so that the margin of the upper is presented in a very convenient position to be pressed down by the wipers 16 against the outwardly extending margin of the 25 sole. Since the grippers will act, on depression of the slide 164, to pull the toe portion of the upper tightly against the upper face of the last before the wipers act on the upper, it is not so important to cause the inner edges of the wipers to press the 30 upper firmly against the sides of the last as they descend toward the sole and thus possibility of damaging delicate shoe uppers by the wiping action of the wipers may be avoided. By adjusting the nuts 178, 202, 202 the initial heightwise position of any of the three grippers may be varied independently of the others.

Under some conditions it may be desirable to cause the toe gripper to apply relatively light tension to the toe end of the upper to facilitate the 40 action of the side grippers in pulling the upper firmly down before the side grippers act on it and also to cause the grip exerted by the toe gripper on the upper to be relieved when the wipers advance and close over the outwardly extending margin of the sole to facilitate forcing the upper at the toe end by the wipers into the angle formed by the outwardly extending margin of the sole and the last. For this purpose there is secured to the rod 168 which operates the toe 50 gripper above the ear 162 a collar 204 which, when a shoe is initially presented to the machine, rests upon a stop lever 206 pivoted at 208 (Fig. 3) on the gripper-operating slide 164. The lever 206 may be rocked to remove it from beneath the 55 collar 204 by the knee of the operator prior to depression of the treadle 169 by which the grippers are operated. When the operator has placed the margin of the upper between the jaws of the three grippers he may swing the lever 206 to one side 60 and thus move it away from under the collar 204. When the stop lever is so swung away the spring 168 upon the lower end of the rod 160 causes the upper jaw 148 of the gripper to snap downward to grip the upper against the lower jaw and, since 65 the spring 168 is stronger than the spring 176 which supports the lower jaw of the gripper, the spring 168 causes the gripper to be pulled downwardly and outwardly somewhat to apply a light tension to the upper. This takes place independently of the operation of the side grippers by the treadle 169 and, when the side grippers have been caused to grip and pull the upper by depression of the gripper-operating treadle 169 70 in the manner previously described and the ma- 75

chine is started into automatic operation by depressing the treadle 94, an adjustable abutment 210 on the wiper-carrying slide 26 engages the rear end portion of the upper jaw 148 of the toe 5 gripper and thus forces the gripper positively downwardly slightly to impart a little further tension to the toe end of the upper, there being at that time a gap between the under face of the collar 204 and the upper face of the ear 162 to 10 allow the necessary small amount of downward movement of the rod 160. The abutment 210 has on its under face a cam surface 212 which acts as the wiper carrier 26 is moved toward the shoe to depress the rear end portion of the upper jaw 15 15 148 further, and the spring 168 being then in expanded condition and the spring 176 in compressed condition, the gripper is supported against further bodily downward movement while the upper jaw 148 is free to rock about its pivot 150 20 in a direction to release its grip on the upper. As the rod 160 is moved upwardly during the releasing movement of the jaw 148 the stop lever 206 will be urged by a spring 214 into position beneath the collar 204 so that it is again in position 25 to be actuated to allow gripping of the upper by the toe gripper early in the next succeeding cycle.

In order to relieve the operator of the necessity of maintaining the treadle 169 depressed during the operation of the wipers, a ratchet 30 plate 216 (Fig. 1) having upwardly directed teeth on its rear edge is secured to the slide 164 and a pawl 218 is pivoted at 220 to the post 10 and cooperates with the plate 216 to hold the slide from upward movement. In order 35 to move the pawl 218 out of engagement with the plate 216 at the conclusion of the machine's operation, upward movement of the wiper-actuating link 64 is utilized to release the pawl 218. Secured to the link 64 is an arm 222 on the front 40 end of which is pivoted a releasing finger 224 which can turn upwardly on its pivot 226 but not downwardly beyond a horizontal position. Formed on a rearwardly projecting portion 228 of the pawl 218 is a wide notch 230. As the 45 link 64 moves downwardly to cause the wipers to descend the finger 224 engages and is lifted by engagement with the end 228 of the pawl and its end falls by gravity into the notch 230. As the link 64 moves upwardly to allow the wipers 50 to rise at the end of their operation, the end of the finger 224 abuts against the upper end of the notch 230 and moves the pawl 218 in a direction to disengage it from the plate 216 so that the grippers may open and rise to their 55 original positions.

In order to prevent the grippers from rising far enough to strike against the lower side of the wipers when the pawl 218 is released, the arm 222 carries an adjustable stop screw 232, and 60 a link 234 is pivoted at its rear end to the bracket 22 and at its forward end to a depending link 236 the upper end of which is pivoted at 165 on the slide 164. When the slide 164 moves upwardly rapidly under the influence of the spring 171, the upper edge of the link 234 65 engages the stop screw 232 and arrests movement of the grippers before they hit the wipers, the wipers and grippers thereafter moving upwardly together.

70 In case it should be desired to tack or staple the margin of the upper to the sole while the wipers remain in operative position instead of securing it by adhesive, the wipers may conveniently have one or more notches cut in their inner edges into which a hand stapling or tack- 75

ing device may be introduced to enable the upper to be fastened to the sole without it being necessary to retract the wipers appreciably from their advanced and closed positions.

In operating the machine, the operator takes 5 a stitch-down shoe comprising an extension sole A and an upper C properly assembled upon a last B and, if it is desired that the marginal flange on the upper be secured in place on the sole by cement instead of by tacking or stapling, 10 the operator then either applies cement to the margins of the sole and/or upper or renders tacky cement which has previously been applied to one or both of these parts. He then places the shoe on the toe-supporting plate 12 of the 15 machine with the toe end of the shoe pointing away from him and abutting against the up-standing rib 18 on the supporting plate. While holding the shoe in this position he places the margin of the upper between the jaws 184, 189 20 of the side grippers and the jaws 146, 148 of the toe gripper which at this time will occupy their raised initial positions with their jaws open. He then depresses the treadle 169 connected to the gripper-operating slide 164 and 25 thus pulls the upper jaws of the grippers downwardly to grip the margin of the upper against the lower jaws. When the downward pressure exerted on the upper gripper jaws on the margin of the upper has become sufficient to overcome the resistance of the springs 176, 194, 194 30 which support the lower gripper jaws, the jaws commence to swing outwardly away from the last and downwardly, the toe gripper about the pivot 142 and the side grippers about the pivots 35 186, 186. The upper is thus tensioned length-wise of the shoe by the toe gripper and pulled away from the last widthwise thereof and toward the toe end of the last by the side grippers. The three grippers also exert a heightwise tension 40 on the upper. As a result the toe portion of the upper is pulled tightly against the upper face of the last, the margin of the upper extending around its toe is held by the grippers in a tensioned outspread condition close to the 45 edge of the outwardly extending margin of the sole, and the opposite sides of the upper along the shank portion are pulled closely against the last. While the pawl 218 maintains the grippers in their lowered and outspread positions, 50 the operator depresses the treadle 94 to effect power operation of the wipers 16 and the heel-end-engaging abutment 108. The bracket 22 now moves downwardly along its guideway 20 and the wipers, having been angularly adjusted 55 to embrace the toe end of the last by operation of the hand wheel 54 with the desired closeness, will wipe the toe portion of the upper downwardly toward the sole while pressing it more or less firmly against the side faces of the last 60 until the wipers engage the outspread margin of the upper held taut by the grippers and press it firmly against the outwardly extending margin of the sole. During this movement the wipers drag the upper, under considerable tension, from between the jaws of the three grippers which remain in their outward and downward positions with their jaws closed throughout the operation of the wipers. During this operation the heel-end-engaging fork or abutment 65 108 swings toward the heel end of the shoe to support it against heelward movement. When the wipers have pressed the outspread margin of the upper firmly against the sole, the spring 70 75 yields and allows the wiper-carrying slide

26 to advance toward the shoe, the wipers being thereby carried over the outwardly projecting margin of the upper while pressing it against the sole in a direction toward the heel end of the 5 shoe and angularly toward each other. These advancing and closing movements of the wipers act to drag the upper completely from between the gripper jaws and to force the upper into the angle between the last and the outwardly 10 projecting marginal portion of the sole, thus fitting the upper to the last and forming therein a well defined crease. The machine comes to rest with the wipers in their advanced and closed positions and the operator may then, if desired, 15 secure the upper to the sole by metallic fastenings by inserting a stapling or tacking tool into the notches in the wipers and driving fastenings to secure the outwardly extending flange of the upper to the outwardly extending margin of the 20 sole. When it is desired to release the shoe, the operator releases the treadle 94 and the bracket 22 moves upwardly, causing the wipers to swing apart and retreat to their original positions, the finger 224 meantime having released 25 the pawl 218 to allow the grippers to rise and open to their initial positions.

Having thus described our invention, what we claim as new and desire to secure by Letters Patent of the United States is:

30 1. A stitchdown lasting machine having, in combination, a support to receive the sole of a stitchdown shoe assembled with an upper upon a last and adapted to support the marginal portion of the sole which projects beyond the bottom of the last, grippers mounted for movement in outwardly and downwardly directed paths with respect to the last, means for closing the grippers upon the upper and moving them in said paths to tension the upper, end-embracing wipers, and means for moving the wipers heightwise 35 of the last to work the upper into the angle between the side of the last and the projecting margin of the sole.

2. A stitchdown lasting machine having, in combination, a support to receive the sole of a 45 stitchdown shoe assembled with an upper upon a last and adapted to support the marginal portion of the sole which projects beyond the bottom of the last, grippers mounted for movement in outwardly and downwardly directed paths 50 with respect to the last, means for closing the grippers upon the upper and moving them in said paths to tension the upper, end-embracing wipers, and means independent of the gripper-operating means for moving the wipers heightwise 55 of the last to work the upper into the angle between the side of the last and the projecting margin of the sole.

3. A stitchdown lasting machine having, in 60 combination, a support to receive the sole of a stitchdown shoe assembled with an upper upon a last and adapted to support the marginal portion of the sole which projects beyond the bottom of the last, grippers mounted upon the support for movement in paths outwardly and downwardly directed with respect to the last, means 65 for closing the grippers upon the upper and moving them in said paths to tension the upper, end-embracing wipers, and means for moving the wipers heightwise of the last to work the upper into the angle 70 between the side of the last and the projecting margin of the sole.

4. A stitchdown lasting machine having, in 75 combination, a support to receive the sole of a stitchdown shoe assembled with an upper upon

a last and adapted to support the marginal portion of the sole which projects beyond the bottom of the last, a toe gripper mounted upon a pivot beneath the support for downward and outward movement with respect to the last, a spring 5 for holding the gripper with its jaws above the support, means acting through a stronger spring for closing the gripper upon the upper and moving it to tension the upper, end-embracing wipers, and means for moving the wipers heightwise 10 of the last to work the upper into the angle between the side of the last and the projecting margin of the sole.

5. A stitchdown lasting machine having, in combination, a support to receive the sole of a 15 stitchdown shoe assembled with an upper upon a last and adapted to support the marginal portion of the sole which projects beyond the bottom of the last, a toe gripper mounted upon a pivot beneath the support for downward and outward movement with respect to the last, a spring 20 for holding the gripper with its jaws above the support, means acting through a stronger spring for closing the gripper upon the upper and moving it to tension the upper, end-embracing wipers, and means independent of the gripper-operating means for moving the wipers heightwise 25 of the last to work the upper into the angle between the side of the last and the projecting margin of the sole.

6. A stitchdown lasting machine having, in combination, a support to receive the sole of a stitchdown shoe assembled with an upper upon a last and adapted to support the marginal portion of the sole which projects beyond the bottom of the last, grippers mounted upon pivots 30 located under the support for swinging movement in paths outwardly and downwardly directed with respect to the last, means for closing the grippers upon the upper and moving them in said paths to tension the upper end-embracing wipers, and means for moving the wipers heightwise 35 of the last to work the upper into the angle between the side of the last and the projecting margin of the sole.

7. A stitchdown lasting machine having, in combination, a support to receive the sole of a 40 stitchdown shoe assembled with an upper upon a last and adapted to support the marginal portion of the sole which projects beyond the bottom of the last, grippers mounted upon the support for movement in paths outwardly and downwardly directed with respect to the last, manually operated means for closing the grippers upon 45 the upper and moving them in said paths to tension the upper, end-embracing wipers, and power-operated means for moving the wipers heightwise 50 of the last to work the upper into the angle between the side of the last and the projecting margin of the sole.

8. A stitchdown lasting machine having, in combination, a support to receive the sole of a 55 stitchdown shoe assembled with an upper upon a last and adapted to support the marginal portion of the sole which projects beyond the bottom of the last, grippers mounted beneath the support for movement in paths outwardly and downwardly directed with respect to the last, manually operated means for closing the grippers upon the upper and moving them in said 60 paths to tension the upper, means for holding the grippers in upper-tensioning position, end-embracing wipers, and power-operated means for moving the wipers heightwise 65 of the last to work the upper into the angle between the side of the last and the projecting margin of the sole.

9. A stitchdown lasting machine having, in combination, a support to receive the sole of a 70 stitchdown shoe assembled with an upper upon a last and adapted to support the marginal portion of the sole which projects beyond the bottom of the last, grippers mounted beneath the support for movement in paths outwardly and downwardly directed with respect to the last, manually operated means for closing the grippers upon the upper and moving them in said 75 paths to tension the upper, means for holding the grippers in upper-tensioning position, end-embracing wipers, and power-operated means for moving the wipers heightwise of the last to work

- the upper into the angle between the side of the last and the projecting margin of the sole.
9. A stitchdown lasting machine having in combination, a support to receive the sole of a stitchdown shoe assembled with an upper upon a last and adapted to support the marginal portion of the sole which projects beyond the bottom of the last, grippers mounted for outward and downward movement with respect to the last, means for closing the grippers upon the upper and moving them to tension the upper, end-embracing wipers arranged for advancing and closing movement with respect to the shoe, and power-operated means for moving the wipers heightwise of the last to work the upper into the angle between the side of the last and the projecting margin of the sole, said power means acting to advance and close the wipers at the conclusion of their heightwise movement.
10. A stitchdown lasting machine having, in combination, a support to receive the sole of a stitchdown shoe assembled with an upper upon a last and adapted to support the marginal portion of the sole which projects beyond the bottom of the last, grippers mounted for outward and downward movement with respect to the last, means for closing the grippers upon the upper and moving them to tension the upper, end-embracing wipers arranged for advancing and closing movement with respect to the shoe, a spring for opposing said advancing and closing movement, and power-operated means for moving the wipers heightwise of the last to work the upper into the angle between the side of the last and the projecting margin of the sole, said power-operated means acting, when further heightwise movement of the wipers is opposed by the projecting margin of the sole, to cause advancing and closing movement of the wipers against said spring.
11. A stitchdown lasting machine having, in combination, a support to receive the sole of a stitchdown shoe assembled with an upper upon a last and adapted to support the marginal portion of the sole projecting beyond the bottom of the last, a toe gripper and side grippers arranged to engage respectively the toe portion and the side portions of the forepart of the upper of a shoe on said support, means for causing the toe gripper to close and pull the upper prior to closing of the side grippers, means for moving the side grippers heightwise of and outwardly with respect to the shoe last, end-embracing wipers arranged for movement heightwise of the last, and means for moving the wipers to work the upper into the angle between the side of the last and the projecting margin of the sole.
12. A stitchdown lasting machine having, in combination, a support to receive the sole of a stitchdown shoe assembled with an upper upon a last and adapted to support the marginal portion of the sole which projects beyond the bottom of the last, two-jaw grippers mounted upon pivots located beneath the support and having their lower jaws initially overhanging the sole-engaging surface of the support, means for moving the upper jaws of the grippers to seize the upper and for swinging the grippers on their pivots to tension the upper outwardly and heightwise with respect to the last, end-embracing wipers, and means for moving the wipers heightwise of the last to work the upper into the angle between the side of the last and the projecting margin of the sole.
13. A stitchdown lasting machine having, in

combination, a support to receive the sole of a stitchdown shoe assembled with an upper upon a last and adapted to support the marginal portion of the sole which projects beyond the bottom of the last, a toe gripper mounted upon a pivot beneath the support for downward and outward movement with respect to the last, a spring for holding the gripper with its jaws above the support, means acting through a stronger spring for closing the gripper upon the upper and moving it to tension the upper, and means for increasing the tension of said stronger spring when the gripper is in initial position, said means being releasable at the will of the operator to cause closing and pulling movement of the gripper.

14. A stitchdown lasting machine having, in combination, a support to receive the sole of a stitchdown shoe assembled with an upper upon a last and adapted to support the marginal portion of the sole which projects beyond the bottom of the last, toe and side grippers mounted upon pivots located beneath the support and having their lower jaws initially overhanging the sole-engaging surface of the support, the pivots of the side grippers converging toward of the shoe, means for moving the upper jaws of the grippers to seize the upper and for swinging the grippers on their pivots to tension the upper outwardly and heightwise with respect to the last, the side grippers because of their converging pivots tending to tension the upper longitudinally, end-embracing wipers, and means for moving the wipers heightwise of the last to work the upper into the angle between the side of the last and the projecting margin of the sole.

15. A stitchdown lasting machine having, in combination, a support to receive the sole of a stitchdown shoe assembled with an upper upon a last and adapted to support the marginal portion of the sole which projects beyond the bottom of the last, two-jaw toe and side grippers mounted upon pivots located beneath the support and having their lower jaws initially above the sole-engaging surface of the support, means for moving the upper jaws of the grippers to seize the upper and for swinging the grippers on their pivots to tension the upper outwardly and heightwise with respect to the last, end-embracing wipers arranged for advancing and closing movement, and means for moving the wipers heightwise of the last to work the upper into the angle between the side of the last and the projecting margin of the sole and for then advancing and closing them to crease the upper into said angle.

16. A stitchdown lasting machine having, in combination, a support to receive the sole of a stitchdown shoe assembled upon its last and adapted to support the marginal portion of the sole which projects beyond the bottom of the last, a toe gripper and side grippers arranged to engage the toe end and side portions of the forepart of the upper of the shoe on said support, manually operated means for moving the grippers heightwise of and outwardly with respect to the shoe last, means for holding the grippers with the upper under tension, end-embracing wipers arranged for movement heightwise of the last, power-operated means for moving the wipers to work the upper into the angle between the side of the last and the projecting margin of the sole, and means operated upon return movement of the wipers to release the gripper-holding means.

17. A stitchdown lasting machine having, in combination, a support to receive the sole of a stitchdown shoe assembled with an upper upon a

- last and adapted to support the marginal portion of the sole which projects beyond the bottom of the last, grippers mounted upon the support for outward and downward movement with respect 5 to the last, means for closing the grippers upon the upper and moving them to tension the upper, a pawl for holding the grippers with the upper under tension, end-embracing wipers mounted for movement perpendicular to said support, power- 10 operated means for moving the wipers heightwise of the last to work the upper into the angle between the side of the last and the projecting margin of the sole and means operating upon return movement of the wipers for releasing said pawl.
- 15 18. A stitchdown lasting machine having, in combination, a support to receive the sole of a stitchdown shoe assembled with an upper upon a last and adapted to support the marginal portion of the sole which projects beyond the bottom of 20 the last, a toe gripper and side grippers arranged to engage the toe and side portions of the forepart of the upper of a shoe on said support, means for operating the grippers heightwise and outwardly with respect to the shoe, end-embracing wipers 25 arranged for advancing and closing movements and for movement heightwise of the last, means

for first moving the wipers heightwise of the last to work the upper into the angle between the side of the last and the projecting margin of the sole and then advancing the wipers, and means operated by the advancing movement of the wipers 5 for releasing the toe gripper.

19. A stitchdown lasting machine having, in combination, a support to receive the sole of a stitchdown shoe assembled with an upper upon a last and adapted to support the marginal portion 10 of the sole which projects beyond the bottom of the last, toe and side grippers mounted upon pivots beneath the support for downward and outward movement with respect to the last, a spring for holding each gripper with its jaw above the 15 support, means acting through a stronger spring for closing each gripper upon the upper and for moving it to tension the upper, and means for increasing the tension of the stronger spring of the toe gripper when that gripper is in initial position, 20 said means being releasable at the will of the operator to cause closing and pulling movement of the toe gripper prior to operation of the side grippers.
